UNITED STATES PATENT OFFICE.

GEORGE M. HUBBARD, OF NEW HAVEN, CONNECTICUT, ASSIGNOR TO THE
W. & E. T. FITCH COMPANY, OF SAME PLACE.

DESIGN FOR A KEEPER FOR SASH-FASTENERS.

SPECIFICATION forming part of Design No. 32,816, dated June 12, 1900.

Application filed May 17, 1900. Serial No. 17,067. Term of patent 14 years.

To all whom it may concern:

Be it known that I, GEORGE M. HUBBARD, of New Haven, in the county of New Haven and State of Connecticut, have invented a new Design for a Keeper for Sash-Fasteners, (Case B;) and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a keeper for a sash-fastener embodying my design; Fig. 2, a top view, and Fig. 3 a rear view, of the same.

This invention relates to a design for a keeper for sash-fasteners; and it consists in the construction and configuration as herein-after described, and shown in the accompanying illustrations.

As herein shown, the back plate or body

portion A is formed with an inverted-V-shaped notch which extends upward into the body and so as to separate the sides, which extend outward, forming securing lugs or 25 projections B, which are provided with screw-holes. The outer edges of the body contract toward the upper end, which is turned forward and downward, forming a lifting and drawing finger C. The edges of the finger, 30 body, and retaining-lugs merge one into the other to produce a symmetrical design.

I claim—

The design for a keeper for sash-fasteners, as herein shown and described.

In testimony whereof I have signed this specification in the presence of two subscribing witnesses.

GEORGE M. HUBBARD.

Witnesses:

FREDK. F. BREWSTER,
JOHN B. FITCH.
